(57) **CLAIM**

The ornamental design for an optical disk cartridge, as shown and described.

DESCRIPTION

FIG. 1 is a front, top and right side perspective view of an optical disk cartridge, showing our new design;

FIG. 2 is a top plan view thereof;

FIG. 3 is a right side elevational view thereof; a left side elevational view being a mirror image thereof;

FIG. 4 is a front elevational view thereof; a rear elevational view being a mirror image thereof;

FIG. 5 is a bottom plan view thereof; and,

FIG. 6 is a front elevational view thereof with a shutter in a slided state.
